UNITED STATES PATENT OFFICE.

FRANK BOGASKIE, OF JOHNSTOWN, NEW YORK.

SAFETY ENVELOPE.

Application filed May 6, 1927. Serial No. 189,398.

My invention relates to envelopes or folders, and particularly to an envelope of the character known as safety envelope.

The general object of my invention is to provide a device of this character which may be sealed in such a way that it is practically impossible to remove the contents without destroying the wrapper. Another object of my invention is to provide a device of this character which may be formed from a single blank, or which, if desired, may be made from separate blanks of extremely simple character and easily assembled into a unitary device.

With these objects in view my invention includes the novel features of construction and the novel combinations and arrangements of elements and features described below and illustrated in the accompanying drawings in which—

Fig. 1 shows the preferred form of the principal blank;

Fig. 2 shows a separate secondary blank which is to be associated with the first blank;

Fig. 3 shows the main blank after the first fold is made;

Fig. 4 shows the secondary blank attached to the main blank after the first fold;

Fig. 5 illustrates how the small blank is thereafter folded;

Fig. 6 shows the next fold in the main blank and illustrates the completed envelope;

Fig. 7 indicates the first sealing operation of the envelope;

Fig. 8 shows the completely sealed envelope;

Fig. 9 is a distorted section of the sealed envelope in the plane 9—9 of Fig. 8;

Fig. 10 illustrates a single blank from which my envelope may be formed;

Fig. 11 illustrates the blank shown in Fig. 10 after several folding operations;

Fig. 12 illustrates the next folding operation;

Fig. 13 illustrates the completely formed envelope;

Fig. 14 illustrates the first sealing operation;

Fig. 15 shows the completely sealed envelope;

Fig. 16 is a distorted section of Fig. 15 in the plane 16—16;

Fig. 17 illustrates a somewhat different

cutting of the single blank from which my envelope may be formed;

Fig. 18 shows the first folding operation;

Fig. 19 the second folding operation;

Fig. 20 the third folding operation; 60

Fig. 21 the fourth folding operation;

Fig. 22 shows the completed envelope;

Fig. 23 shows the first sealing operation;

and Fig. 24 shows the completely sealed envelope. 65

Throughout the drawings, the sectioned portions represent areas of adhesive; dotted lines represent lines of fold; and solid lines represent edges or slits.

Referring particularly to Figs. 1, 2, 3, 4, 5, 6, 7, 8 and 9, my preferred envelope is formed from two separate blanks; 1 representing generally the main blank and 2, the small or secondary blank. The main blank 75 comprises a body portion, 3, which forms the front of the envelope, laterally extending flaps, 4 and 5, respectively, which form the inner back of the envelope, a sealing flap, 6, and a flap, 7, which forms the outer back 80 portion of the envelope.

In forming my envelope, the laterally extending flaps, 4 and 5, are first overfolded the body portion, 3, and sealed together as shown in Fig. 3. After the lateral flaps 85 have been overfolded, the secondary blank, 2, is attached to the outside thereof by means of the adhesive, 8, and is thereafter riveted to the flaps, 4 and 5, by the rivets, 9, as shown in Fig. 4. The secondary blank, 2, 90 comprises a body portion, 10, laterally extending flaps, 12 and 13, and oppositely disposed flaps, 14 and 15. After the secondary blank is secured to the main blank, the flap, 15, is overfolded the body portion, 10, along 95

the line, 16, the flap, 12, is then overfolded and sealed on the flap, 15, and the flap, 14, is finally overfolded the whole and sealed to form a long narrow pocket or envelope open at the end, 13. The next step in the 100 formation of my envelope is to overfold the flap, 7, along the dotted line, 18, to the position shown in Fig. 6, where it is secured to form the completed envelope. The portion, 69, of flap, 7, is folded over along the dotted line, 70, and affords a protection to the contents of the envelope. From a consideration of the foregoing it will be apparent that my envelope has a back of double thickness and that there is a long narrow tube or 110

pocket within this double back which is formed from the small blank, 2. This pocket is open at the end, 13.

In sealing my envelope after the contents have been put in the compartment, the flap, 6, is overfolded the back of the envelope and sealed thereon by means of the adhesive. A long shank riveting instrument is then inserted through the opening, 13, into the passage or pocket formed by the secondary blank, and rivets, 19, are inserted through the flap, 6, the outer back of the envelope formed from the flap, 7, and through the outer side of the pocket formed by the secondary blank. These rivets are clinched on the inside, and it will be apparent that it is quite impossible to unclinch them from the exterior of the envelope. These rivets in connection with the rivets, 9, fasten all of the folded portions of the envelope together and it cannot be opened without tearing.

Referring to Figs. 10 to 15 inclusive, 1 have here shown how my complete envelope may be formed from a single unitary blank. 25 This blank is quite similar in its general contour to the blank shown in Fig. 1, and comprises a body portion, 20, lateral flaps, 21 and 22, a sealing flap, 23, and a flap, 24, which, in addition to forming the outer back 30 of the envelope is also cut to form the pocket or passage into which the riveter is inserted. The lateral flaps, 21 and 22, may be provided with secondary flaps, 25 and 26, respectively, to be folded within the envelope compartment to provide a protection for the contents. The main compartment is formed by overfolding the flaps, 21 and 22, upon the body of the envelope and along the dotted lines, 27 and 28, respectively. The 40 flap, 24, is then overfolded the lateral flaps along the dotted line, 29. After these operations the folded blank appears substantially as shown in Fig. 11, except that the portions, 30 and 31, of the flap, 24, are shown as 45 downfolded over the portion, 34, and along the dotted lines, 32 and 33, respectively. In forming the long narrow pocket, the portions, 30, 31, and 35, are next together overfolded the portions, 36 and 37, along the dotted line, 38, and the bottom of the pocket 50 is formed by thereafter overfolded and sealing the flap, 39. After these operations, the envelope appears as shown in Fig. 12. The envelope is then completed by folding or 55 rolling the pocket, 40, over upon the portion, 41, about the dotted line 42, and the portions, 35 and 37, which lie together are pushed through the opening formed by tongue, 37, and brought up to the positions 60 shown in Fig. 13. Rivets, 43, are then inserted through tongues, 44 and 45, and clinched on the inside of the envelope compartment and another rivet, 43, is passed through the overlying portions, 35 and 37, 65 the contiguous portions of the flaps, 21 and

22, and clinched on the inside of the envelope compartment. This structure in its essential details is substantially identical with my envelope shown in Fig. 6 except that it is formed in a slightly different way. 70 After the contents has been placed in the envelope compartment, the flap, 23, is sealed over the back of the envelope as shown in Fig. 14 and the rivets, 46, are placed by means of a long shank riveting instrument 75 inserted through the opening, 71, in the pocket, and clinched within the pocket. The flap, 47, is intended to be sealed over the opening in the pocket although it would be quite impossible to unclinch the 80 rivets by an instrument inserted through this opening if it were not closed.

Referring to Figs. 17 to 24 inclusive, I have here shown how my envelope may be formed from a single blank in a slightly 85 different way from that shown in Figs. 10 to 15 inclusive. Generally speaking, the blank shown in Fig. 17 is identical with the blank shown in Fig. 1 except that the laterally extending flaps, 48 and 49, are provided with 90 secondary flaps, 50 and 51, from which the secondary pocket or compartment is formed. In other words instead of forming the secondary pocket from a portion of the flap, 52, in accordance with the description in respect of Figs. 10 to 15 inclusive, the pocket is formed from portions of the flaps, 50 and 51.

In forming the envelope from the blank shown in Fig. 17, the flaps, 48 and 49, carrying flaps, 50 and 51, are overfolded the body, 53, of the envelope to the position shown in Fig. 18. The flaps, 50 and 51, which are then fastened together by means of the adhesive shown on the flap, 51, are folded 100 along the dotted line, 52, and against the backs of the flaps, 48 and 49. In this position they appear as shown in Fig. 19, which is analogous to Fig. 11. The small pocket is then formed by successively rolling or 105 overfolding the portions, 72 and 73, along the dotted lines, 54 and 55, to the position shown in Fig. 20, and then folding once more along the dotted line, 56, and bringing the overlying portions, 57 and 58, around 110 through the opening left by tongue, 57, and up to the position shown in Fig. 21. In forming the pocket, the tongues, 59 and 60, are raised, and finally overlie the pocket, as shown in Fig. 21. In this position rivets, 115 61, are inserted through the tongues and through the back of the envelope and clinched on the inside of the main compartment. The flap, 52, is then folded over the whole along the dotted line, 63, and sealed 120 thereto by means of the adhesive. Further, a rivet, 64, is then inserted through the flap, 52, the overlying flaps, 57 and 58, and the contiguous portions of the flaps, 48 and 49, and clinched on the inside of the envelope 125 130

compartment as shown in Fig. 22. This is my completed envelope.

After the contents has been placed in the envelope, the sealing flap, 65, is folded over the opening and secured to the back by means of the adhesive. Thereafter, a long shank riveting instrument is inserted through opening, 66, in the secondary pocket, and rivets, 67, are passed through the flap, 65, and clinched on the inside of the secondary pocket. The opening, 66, is then sealed by means of the flap, 68.

It will be apparent from the foregoing that envelopes embodying the essential features of my invention may be formed in several different ways and from a single unitary blank or from assembled blanks. In either case, it will be obvious that because of the limited accessibility to the places where the rivets are clinched it will be quite impossible to open the sealed envelope without cutting or tearing. All of the overfolded portions are not only adhesively secured together but also fastened by rivets which cannot be removed without tearing the paper.

While I have described my invention in its preferred forms and illustrated several different methods of construction, it is to be understood that the words which I have used are words of description rather than of limitation and that changes within the purview of the appended claims may be made without departing from the true scope and spirit of my invention in its broader aspects.

35 What I claim is—

1. In a safety envelope having overfolded portions forming the front and back of a main compartment, a main sealing flap therefor, and a flap overfolded upon the back of the main compartment, means lying between the back of the main compartment and said overfolded flap and forming, independently thereof, a substantially inaccessible pocket provided however with a comparatively small opening for the insertion of a riveting instrument.

2. In a safety envelope having overfolded portions forming the front and back of a main compartment, a main sealing flap therefor, and a flap overfolded upon the back of the main compartment, means forming, independently of said overfolded flap and the

portions forming the main compartment, a pocket within said envelope, and inaccessible except through a comparatively small opening provided for the insertion of a riveting instrument.

3. In a safety envelope, means forming a main compartment, a main sealing flap therefor, and means, independent of the main compartment forming means, forming a pocket of limited accessibility lying beneath said flap when sealed; said pocket being provided with a comparatively small opening therein for the insertion of a riveting instrument.

4. A safety envelope comprising front and back portions forming a main compartment, a flap adapted to close said compartment, and means riveted to the back of said envelope and forming, independently thereof, a pocket adapted to lie beneath the main flap when sealed; said pocket being inaccessible except through a comparatively small opening provided for the insertion of the riveting instrument.

5. A safety envelope having a main sealing flap and provided with two independently walled compartments; one of said compartments being the main compartment and the second of said compartments lying beneath the main flap when sealed and being comparatively narrow and inaccessible except through a comparatively small opening provided for the insertion of a riveting instrument.

6. In a safety envelope, means forming a main compartment, a main sealing flap therefor, and means forming a comparatively narrow tube lying beneath the zone covered by the main flap when sealed; the interior of said tube being inaccessible except through a comparatively small opening provided for the insertion of a riveting instrument.

7. In a safety envelope comprising means forming a main compartment and a sealing flap therefor, a comparatively narrow tube secured to the back of said compartment and adapted to lie beneath the zone covered by the flap when sealed; the interior of said tube being inaccessible except through a small opening provided for the insertion of a riveting instrument.

FRANK BOGASKIE.
